Primary Examiner—Mimosa De(74) *Attorney, Agent, or Firm*—Cislo & Thomas, LLP(57) **CLAIM**

I claim the ornamental design for a china cabinet/buffet, as shown and described.

DESCRIPTION

FIG. 1 is a perspective view of my china cabinet/buffet;

FIG. 2 is a front view thereof;

FIG. 3 is a left side view thereof;

FIG. 4 is a right side view thereof;

FIG. 5 is a top view thereof;

FIG. 6 is a close-up front view of the banded portion at the upper right side 6a shown in FIG. 2 thereof;

FIG. 7 is a close-up front view of a lateral drawer 6b shown in FIG. 2 thereof;

FIG. 8 is a close-up front view of the center drawer 6c shown in FIG. 2 thereof; and,

FIG. 9 is a close-up front view of the banded portion under the drawers 6d shown in FIG. 2 thereof.

The broken lines are for environmental purposes only and form no part of the claimed design.
